CLAIM

The ornamental design for a wall hook, as shown and described.

DESCRIPTION

FIG. 1 is a front perspective view of a wall hook showing our new design;

FIG. 2 is a rear perspective view thereof;

FIG. 3 is a front view thereof;

FIG. 4 is a right side view thereof;

FIG. 5 is a left view thereof;

FIG. 6 is a top view thereof; and,

FIG. 7 is a bottom view thereof.

The broken line representing the rear surface of the wall hook represent disclaimed subject matter and forms no part of the claimed design.

1 Claim, 5 Drawing Sheets
